DESIGN FOR A PAPERWEIGHT OR LIKE ORNAMENT

Harry E. Geron, Springfield, Ohio

Application April 11, 1947, Serial No. 138,311

Term of patent 7 years

(Cl. D74—12)

To all whom it may concern:

Be it known that I, Harry E. Geron, a citizen of the United States and a resident of Springfield, in the county of Clark and State of Ohio, have invented a new, original, and ornamental Design for a Paperweight or Like Ornament, of which the following is the specification, reference being had to the accompanying drawings, forming part thereof wherein:

I claim:

The ornamental design for a paperweight or like ornament, substantially as shown.

HARRY E. GERON.
